UNITED STATES PATENT OFFICE.

CHARLES H. McCREADY, OF TULSA, AND PAUL C. McCREADY, OF BARTLESVILLE, OKLAHOMA.

LATCH MECHANISM FOR DEEP-WELL PUMPS.

Application filed March 18, 1925. Serial No. 16,296.

To all whom it may concern:

Be it known that we, CHARLES H. McCREADY and PAUL C. McCREADY, citizens of the United States, residing at (1) Tulsa, (2)

5 Bartlesville, in the counties of (1) Tulsa, (2) Washington, and State of Oklahoma, have invented a certain new and useful Improvement in Latch Mechanism for Deep-Well Pumps, of which the following is a 10 full, clear, and exact description, reference being had to the accompanying drawings.

This invention relates to an improved latch mechanism for use in deep well pumps of the kind disclosed and claimed in Letters

15 Patent No. 1,494,069, granted to us on May 13, 1924.

The object of our present invention is to so improve the construction and design of the latch mechanism of the pump as to render it stronger, more positive of action, and more reliable than the latch mechanism disclosed in the aforesaid patent.

In our present latch construction, the holding power of the jaws increases with the 25 application of the load; the jaws are supported by shoulders or abutments which serve to remove the strain from the pins on which the jaws are pivoted; and (there being two pairs of jaws) the jaws of each pair are 30 so interconnected that the movements of one jaw of each pair is positively transmitted to the other.

With the foregoing objects in view, our invention may be defined as consisting of the 35 combination and arrangement of parts illustrated in the accompanying drawings and set out in the claims annexed hereto.

In the drawings, Fig. 1 is a central vertical section through a pump incorporating 40 our improved latch mechanism; Fig. 2 is a similar view of the upper end of the pump showing the latch mechanism released from the sleeve piston, as when the sucker rods are being withdrawn from the well tubing; Fig. 45 3 is a central vertical section through the pump barrel in the region of the upper end of the sleeve piston and through the latch mechanism, the view being on a scale approximately double that of the preceding views; Figs. 4 and 5 are transverse sections

on the lines 4—4 and 5—5, respectively, of Fig. 3; Fig. 6 is a perspective view of the latch body or frame; and Fig. 7 is a similar view of one of the latch jaws.

The pump comprises an outer barrel 1 and 55 an inner barrel 2 which are spaced apart and rigidly connected together at their lower ends by a base 3. The base is shown as terminating at its upper end in an internally threaded flange 4 within which the threaded lower end of the barrel 1 is screwed and as having a bore 5 which is internally threaded at its upper end for the reception of the threaded lower end of the barrel 2. Adjacent its lower end, the latter barrel is provided with a plurality of openings 6 through 60 which the interiors of the two barrels communicate. A shoe 7 is applied to the lower end of the base 3 and supports a standing valve assembly 8 which is fitted within the bore 5. A reducing coupling 10 is threaded onto the upper end of the outer barrel 1 and connects the same to the lower end of the well tubing 11. It will be observed that the inner surface of the coupling 10 tapers from 65 the internal diameter of the barrel 1 to that of the tubing 11.

Operating within the inner barrel 2 is a 70 valved piston 12, commonly known as a working valve. The valve 13 which is incorporated in the piston 12 is of the usual ball type and opens as the piston descends to permit the fluid which is below the piston to pass above the same and closes as the piston ascends to lift the body of fluid thereabove. The piston 12 is connected in the usual way 75 to a sucker rod section 15. This rod section has applied to its upper end a latch body or frame 16 which, in turn, has its upper end connected to a string of sucker rods, the lower section of which is designated 17.

According to the present embodiment of the invention, the latch body or frame 16 is 80 substantially square in cross section, is equipped with a threaded pin 18 at its upper end for entrance into the standard socket 19 of the sucker rod section 17 and at its lower end is provided with a socket 20 for the reception of the standard pin 21 of the sucker rod section 15. A rectangular opening 22 85

100

extends through the body or frame 16 and within this opening the latch jaws 25 are movably supported. The latch jaws are identical and therefor interchangeable and 5 are arranged in pairs, one pair protruding from each side of the opening 22. Each jaw, at one end, is provided with a hole 26 (Fig. 7) and at its opposite end is formed with a recess 27 and a projection 28. The latter end 10 of the jaw has a keeper-engaging face 29. A recess 30 is formed in the inner side of each of the jaws intermediate its ends. The jaws of each pair are reversed with respect to each other, the projection 28 of one occupying the recess 27 of the other, and the four jaws are pivotally supported on pins 31 whose ends are confined within holes 32 in the latch body or frame 16. The outer ends 15 of the holes 32 may be counterbored and the ends of the pins riveted therein. The opposite ends of compression springs 33 are confined within the recesses 30 of the corresponding jaws of the opposed pairs and these springs tend to force the jaws outwardly. 20 Attention is directed to the fact that the pivoted ends of the jaws bear against the end walls of the opening 22 thereby to remove the thrust of the jaws from the pins 31 when the mechanism is in action.

30 Operating within the space between the outer barrel 1 and the inner barrel 2 is a sleeve piston 35 which is fitted at its lower end with piston rings 36 to effect a fluid tight joint with the outer barrel. Likewise, 35 the upper end of the inner barrel 2 is fitted with rings 37 which engage the inner surface of the sleeve piston 35. Connected, as by screw threads, to the upper end of the sleeve piston 35 is a top 40, and clamped 40 between an internal shoulder 41 thereof and the upper end of the sleeve piston is a keeper 42 which is in the nature of a ring having top and bottom surfaces that are in planes substantially perpendicular to lines 45 drawn radially from the pivotal axes of the jaws 25. A wiper ring 43, similar to those designated 36 and 37, is confined within a circumferential groove of the top 40 and bears against the inner surface of the 50 outer barrel 1.

When the parts are in readiness for use, the keeper 42 is engaged between the opposed faces 29 of the two pairs of jaws 25 thereby to lock the sleeve piston to the sucker rods, and as the sucker rods are reciprocated by the pumping apparatus, the pistons 35 and 12 are moved up and down within the respective barrels 1 and 2.

It may be explained briefly that, as the 60 pistons rise, fluid is drawn into the inner barrel and, through the openings 6, into the outer barrel, the standing valve 8 opening to permit of the ingress of the fluid. As the piston descends the standing valve is 65 maintained closed and the fluid within the

space between the inner and outer barrels is forced through the openings 6 into the inner barrel and it, with the fluid formerly contained within the inner barrel, rises past the valve 13 of the piston 12. On the subsequent ascending stroke of the pistons the fluid above will be lifted and a new charge of fluid drawn into the lower ends of the inner and outer barrels 1 and 2.

When the sucker rods are "pulled", as for 70 the purpose of inspecting the piston 12 or renewing the cups thereof, the upper latch jaws 25 engage the converging inner wall of the coupling 10 and are forced inwardly thereby, and by reason of the connection between the upper and lower jaws through the projections 28, the lower jaws are also retracted thereby to disengage the jaws completely from the keeper 42. As soon as 80 the latch mechanism is thus released from the keeper, said mechanism withdraws from the sleeve piston, leaving said piston in the position wherein it is shown in Fig. 2, while the sucker rods, latch mechanism, and piston 12 may be withdrawn through 85 the tubing 11 in the usual way. Upon the replacement of the parts the lower jaws 25 pass through the keeper 42 and the springs 33 expand the jaws and engage their faces 29 with the upper and lower sides of 90 the keeper 42, whereupon the parts are coupled together and the pumping operation 95 may be resumed.

Having thus described our invention, 100 what we claim is:

1. In a pump of the character set forth, the combination of a pump barrel, a sleeve piston, piston reciprocating means, a latch body carried by said piston reciprocating means, a pair of jaws movably connected to the body and arranged one above the other and having faces for engagement with abutment portions on the sleeve piston, and means for disengaging the jaws from the sleeve piston as the piston reciprocating means is withdrawn from the pump barrel.

2. In a pump of the character set forth, the combination of a pump barrel, a sleeve piston, piston reciprocating means, a latch body carried by said piston reciprocating means, a pair of jaws pivotally connected to the body and arranged one above the other and having faces for engagement with abutment portions on the sleeve piston, the jaws having thrust bearing on parts of the latch body, and means for disengaging the jaws from the sleeve piston as the piston reciprocating means is withdrawn from the pump barrel.

3. In a pump of the character set forth, 125 the combination of a pump barrel, a sleeve piston, piston reciprocating means, a keeper on the sleeve piston, a latch body carried by said piston reciprocating means, jaws movably connected to said body and

having opposed faces between which the keeper is adapted to be engaged, and means for automatically disengaging the jaws from the keeper as the piston reciprocating means is withdrawn from the pump barrel.

4. In a pump of the character set forth, the combination of a pump barrel, a sleeve piston, piston reciprocating means, a keeper on the sleeve piston, a latch body carried by said means, jaws movably connected to the body and having opposed faces between which the keeper is adapted to be engaged, said jaws being interconnected so that movement of one is imparted to the other, and an abutment arranged to be engaged by one of said jaws as the piston reciprocating means is withdrawn from the pump barrel thereby to disengage the jaws from the keeper.

5. In a pump of the character set forth, the combination of a pump barrel, a sleeve piston, piston reciprocating means, a keeper on the sleeve piston, a latch body carried by said piston reciprocating means, jaws pivotally connected to said body and having opposed faces that are adapted to engage the upper and the lower faces of the keeper, means tending to swing the jaws to keeper engaging position, the jaws being interconnected so that the movement of one is imparted to the other, and an abutment arranged to be engaged by one of said jaws as the piston reciprocating means is withdrawn from the barrel thereby to disengage the jaws from the keeper.

6. In a pump of the character set forth, the combination of a pump barrel, a sleeve piston, piston reciprocating means, a keeper on the sleeve piston, a latch body carried by the piston reciprocating means, two pairs of jaws pivotally connected to the body, the jaws of each pair being arranged one above the other and having opposed faces that are adapted to engage the upper and lower sides of the keeper, springs compressed between the corresponding jaws of the two pairs and tending to swing the jaws outwardly into keeper engaging position, the jaws of each pair being interconnected so that movement of one is imparted to the other, and an abutment arranged to be engaged by the corresponding jaws of the two pairs as the piston reciprocating means is withdrawn from the pump barrel thereby to retract all of said jaws and disengage them from the keeper.

7. In a pump of the character set forth, the combination of a pump barrel, a sleeve piston, piston reciprocating means, a keeper on the sleeve piston, a latch body carried by the piston reciprocating means, two pairs of jaws pivotally connected to said body, the jaws of each pair being disposed one above the other and having opposed faces that are adapted to engage the upper and lower sides

of the keeper, said jaws having also one a recess and the other a projection entering said recess whereby the movement of one jaw is imparted to the other, means tending to project the jaws to keeper engaging position, and an abutment arranged to be engaged by the corresponding jaws of the two pairs and retract the jaws from keeper engaging position as the piston reciprocating means is withdrawn from the barrel.

8. In a pump of the character set forth, the combination of a pump barrel, a sleeve piston, piston reciprocating means, a keeper on the sleeve piston, a latch body carried by the piston reciprocating means, jaws pivotally connected to said body and having opposed faces for engagement with the upper and lower sides of the keeper, the latched body having parts wherewith the jaws abut so that said parts receive the thrust of the jaws, and means for disengaging the jaws from the keeper as the piston reciprocating means is withdrawn from the pump barrel.

9. In a pump of the character set forth, the combination of a pump barrel, a sleeve piston, piston reciprocating means, a keeper on the sleeve piston, a latch body carried by the piston reciprocating means and having a transverse opening, two pairs of opposed jaws pivotally supported within said opening and arranged to bear against the end walls thereof, the jaws of each pair being disposed one above the other and having opposed faces that are adapted to engage the upper and the lower sides of the keeper, the jaws of each pair also having interengaging parts through which the movement of one jaw is imparted to the other, means tending to project the jaws to keeper engaging position, and an abutment arranged to be engaged by the corresponding jaws of the two pairs thereby to retract the jaws as the piston reciprocating means is withdrawn from the piston and thus disengage the jaws from the keeper.

10. In a pump of the character set forth, the combination of a pump barrel, a sleeve piston, piston reciprocating means, a keeper on the sleeve piston, a latch body carried by the piston reciprocating means and having a transverse opening, two pairs of identical, interchangeable jaws, each jaw having at one end a hole and at the other end a keeper engaging face as well as a recess opening through said face and a projection extending beyond said face, two pivot pins carried by the latch body adjacent each end of the aforesaid opening and extending through the holes of the corresponding jaws of the two pairs, springs compressed between the corresponding jaws of the two pairs and tending to swing said jaws to keeper engaging position, the projection of each jaw of each pair occupying the recess of the other jaw of said pair, an abutment

arranged to be engaged by the corresponding jaws of the two pairs as the piston reciprocating means is withdrawn from the barrel thereby to retract the jaws from keeper engaging position.

11. In a pump of the character set forth, the combination of a sleeve piston, piston reciprocating means, a top threaded onto the sleeve piston and having a shoulder opposed

to the end of said piston, an annular keeper 10 clamped between said shoulder and said end of the piston, and latch mechanism carried by the piston reciprocating means for co-operation with the keeper.

In testimony whereof, we hereunto affix 15 our signatures.

CHARLES H. McCREADY.
